SELF-EXTINCTION OF CORONA DISCHARGE IN ELECTRICAL APPARATUS
Bernhardt J. Eiseman, Jr., Wilmington, Del., assignor to E. I. du Pont de Nemours and Company, Wilmington, Del., a corporation of Delaware
Filed Jan. 22, 1962, Ser. No. 167,675
7 Claims. (Cl. 174—17)

This invention relates to electrical devices, and more particularly to those employing gaseous dielectrics.

It is known that, in electrical devices such as those in which electrical conductors of different potentials are arranged near each other, various types of discharges between the conductors are possible and all too frequently occur, such as the spark-over or arcing, glow discharge, point discharge, silent electrical discharge, and corona (or crown discharge). Often fluids, both gases and liquids, are used to prevent the arcing or spark-over discharge. Where gases are used as the dielectric, the other types of discharges are quite frequent. The glow discharge, however, which takes place only at greatly reduced pressures, does not ordinarily occur in the general types of electrical apparatus.

The present invention is more particularly directed to a method for reducing the corona discharge which occurs when highly stressed, non-uniform electrical fields exist over restricted areas. In the present invention, the term "corona" discharge will be used to include the so-called point discharge and silent electrical discharge which in many cases are referred to as "corona".

In this type of discharge, ordinarily the current flow is self-limiting although typical examples of a corona discharge occur where voids exist in solid insulation or between conductors which, due to imperfections, do not have a uniform surface. Unlike the glow discharge, the corona discharge occurs at about 0.1 atmosphere pressure and above. While various methods have heretofore been employed in an attempt to control corona discharge, none of them has been completely satisfactory. Unlike arcing or spark-over which causes immediate damage to electrical equipment, the corona discharge gives slow but cumulative effects which in many cases are serious since they cause deterioration of solid, liquid and gaseous insulating materials.

It is an object of the present invention to provide electrical apparatus in which the corona discharge will be self-extinguishing, by employing as the gaseous dielectric, or as an addition to the gaseous dielectric, a material which under the influence of the corona discharge will produce a non-conducting or semi-conducting coating on the conductor at the point or over the area of discharge.

It has now been found that corona discharge in electrical apparatus, in which gases are used as the dielectric material alone or in conjunction with other dielectric material, can be effectively reduced by employing a gaseous dielectric which, under the influence of the corona, produces a non-conducting or semi-conducting solid on the point or over the area at which the corona discharge occurs. The gaseous dielectrics with which the present invention is concerned are those which normally prevent the arcing (spark-over) between conductors under normal

2

operating conditions. The gaseous dielectrics generally employed for this purpose have been found to be ineffective against corona discharge in the apparatus in which they are employed, such as in transformers, shielded high voltage electric cables, capacitors, condensers or similar types of apparatus. In all such devices conductors under different electric potentials exist relatively close to each other, and in such devices corona can and often does occur particularly where high voltages exist or where such occur 5 even momentarily such as in the starting of electrical motors or where overloads occur in the conductors.

Corona occurs where a field of high electrical stress exists, such as where voids exist in solid insulation on wires or where the normal smooth surface of the conductor is marred by points or burrs such as those which occur on wire due to the imperfections in the wire-drawing process.

Corona often can be detected visually, particularly in total darkness, where it appears as a faint glow. Other 20 forms of the same phenomena may not be apparent visually. A more convenient and much more sensitive method for detecting corona discharge in any form is by the use of a cathode ray oscilloscope, such as described hereinafter.

25 As previously stated, the present invention contemplates adding to a gaseous dielectric a gaseous material or a low boiling liquid which under conditions of operation of the apparatus has a substantial vapor pressure and which under the influence of the corona discharge itself 30 forms a resinous material. The compounds used in the present invention are organic compounds which either by themselves or in combination with the gaseous dielectric with which they are used under the influence of an ionizing electrical discharge, form resinous deposits on the conductor at the point where the corona discharge occurs. Since it has been found that these deposits are either non-conductors or semi-conductors, the extinguishment of the 35 corona is believed to be due to the spreading of the stressed electrical field over a larger area and thus diminishing the stress, or by more completely insulating the area where the corona originally takes place.

The corona extinguishing substances of the present invention may also be used as the gaseous dielectric itself if it has the necessary dielectric and other properties. In general, however, they will be used as additives to gaseous dielectrics which do not themselves cause self-extinguishment of corona. It is of course necessary to have a sufficient amount of the corona extinguishing gas present to produce a coating for the corona-producing area when the corona discharge takes place. The minimum partial pressure of the corona-suppressing substance should be at least about 10 mm. of mercury. Of course no upper limit is set since the corona-suppressing substance may be the dielectric material itself, in which case 50 the total pressure would be that of the corona-suppressing substance.

It is of course understood that there is a corona starting voltage for a given system depending on both the dielectrics and the conductors and the configuration of 55 the conductors. When the starting voltage is exceeded, corona occurs. It is frequently possible to extinguish corona without changing the voltage, such as by increasing the pressure of the dielectric gas or by replacing part of

the dielectric gas with a material having better dielectric properties, but these methods give only temporary relief without correcting the factors which tend to produce the corona. "Self-extinguishment of corona" is used herein to mean that, after the corona starting voltage has been exceeded and corona is occurring, the corona will extinguish itself without any other change being made. This has the advantage of being automatic in nature, whereby the corona is extinguished even without knowledge that the corona discharge is taking place.

In general, the compounds which according to the present invention may be used for self-extinguishment of corona will be those organic compounds which in the presence of an ionizing electrical discharge produce a polymeric coating material, usually resinous in character, which is a non-conductor or a semi-conductor of electricity. A number of gaseous compounds of this type have been described in the published literature. As illustrative of this type of compound may be mentioned: benzene, toluene, perfluorobenzene, vinyl fluoride, vinylidene fluoride, tetrafluoroethylene, acrylonitrile, butadiene, cyclohexene, ethylene, isobutylene, propylene, cyclohexane, neopentane, octafluoro-1,4-dithiane, propylene oxide, 1,4-dioxane, and nitromethane.

The above-mentioned compounds which may be used for self-extinguishment of corona will generally be added in relatively small amounts to the usually gaseous dielectric materials, although, as stated above, they can be used along where they exhibit the otherwise required dielectric properties. In addition to the particular dielectric materials disclosed in the specific examples, the following further exemplify the gaseous dielectrics with which the compounds of the present invention may be employed: 2-chloroheptafluoropropane, decafluorobutane, chloropentafluoroethane, octafluoropropane, hexafluoroethane, 1,2-dichlorotetrafluoroethane, 1,1,2-trichlorotrifluoroethane, perfluoro-(2-n-butyltetrahydrofuran), perfluorotrimethylamine, chlorotrifluoromethane, carbon tetrachloride, nitrogen, helium, hydrogen, carbon dioxide. It is of course understood that the corona-extinguishing compounds of the present application may be used with any gaseous dielectric since quite obviously under the conditions employed in their use as dielectrics there will normally be no reaction between the corona extinguishing compounds and the dielectric materials.

The following examples are based on tests of the corona extinguishing compounds which have been carried out in an apparatus more particularly illustrated in the attached drawing which forms a part of the present application. In this drawing, FIGURE 1 shows the test apparatus, while FIGURE 2 is a wiring diagram for a cathode ray oscilloscope circuit used in detecting corona discharge even where it was not apparent visually.

The apparatus of FIGURE 1 of the drawing comprises a common three-necked, round-bottomed flask 1, which can conveniently be of 500 cc. capacity. Rubber stoppers (polychloroprene) 2, 3 and 4 were used. Through stopper 2 there is sealed a copper wire 5 to which is attached a small alligator clamp 6 in which a steel needle 7 is held. Through stopper 3 is sealed a $\frac{1}{4}$ " outside diameter copper tube 8, the end 9 of which is crimped closed and soldered. The end of needle 7 is adjusted to about $\frac{1}{4}$ " from the nearest point on the tube 8. Through the center stopper 4 an inlet copper tube 10 is provided to permit the removal and introduction of various gaseous materials to the system. The leads of the secondary winding of a 10,000 volt transformer 11, see FIGURE 2 (secondary rated at 23 milliamperes), are attached through a circuit as illustrated in FIGURE 2 of the drawing to electrodes 5 and 8. The primary windings of the transformer are attached to a source of electric power through a variable transformer 12 so that there can be supplied to the primary windings a voltage ranging from 0 to 130 volts of alternating current.

Observations were sometimes made visually by con-

necting the 10,000-volt transformer, 11, directly to the electrodes 5 and 8, leaving out the remainder of the circuit of FIGURE 2.

The tests were carried out at approximately room temperature (about 77° F.). If a single substance was being tested, the flask was evacuated to approximately 0.05 mm. Hg. pressure and the material to be tested was then introduced into the flask. Where the material to be tested was a gas at room temperature and atmospheric pressure, sufficient of this gas was introduced to bring the pressure to the desired level as given in the specific examples. If the material was a liquid, the vapor of the liquid was introduced into the flask to provide the vapor pressure specified in the examples. When mixtures of gases were used, or mixtures of gases with relatively volatile liquids, the gas of lower molecular weight was introduced first, then the second gas of higher molecular weight was introduced. The partial pressures of each material of course determined the mol ratio of the materials that were used in the flask. Usually where mixtures were employed, a small area of the side of the flask was heated to cause convection in the cell to produce more rapid mixing of the gases. This was repeated several times to provide thorough mixing. Where vapors of liquids are used, the liquid itself may be introduced into the flask to provide the desired vapor pressure. For best results, the rubber stoppers in the flask were changed frequently to prevent absorbed materials from contaminating materials in subsequent tests.

While the corona in many cases could be observed visually when the test was run in a darkened room, the use of a cathode ray oscilloscope gave much more accurate determination of the presence or absence of corona discharge.

In the following examples the voltage applied as read on the voltmeter 13 was generally increased until corona was observed either visually or by the oscilloscope. In the examples the voltage given is that actually used on the secondary winding of the transformer calculated from the voltmeter reading of the voltage of the primary winding as shown on the drawing, using a factor of 86.8. If the corona extinguished itself, the effect of increased voltage was determined. It is to be understood that there is a limiting voltage that can be applied to any system, above which arcing takes place. The voltage which can be used is determined by the materials in the system and their pressures. If the voltage is maintained near the spark-over or arcing voltage, permanent suppression of corona will usually not be obtainable, so that the tests are run at voltages below that which results in arcing.

FIGURE 2 of the drawing illustrates the external circuit employed with the apparatus of FIGURE 1 where a cathode ray oscilloscope 16 is used. Since this oscilloscope is a standard commodity of commerce, the internal circuits are not shown. The circuit shown inside the dotted-line rectangle produces an elliptical Lissajous figure as at 15 on the oscilloscope 16, with the major axis substantially horizontal. The vertical dimension of the Lissajous figure was adjusted by means of a 100K ohm resistor 17. When corona occurred, it appeared on the oscilloscope as vertical lines superposed on the Lissajous figure 15. The electrodes from the test cell or flask 1 in FIGURE 1, which in FIGURE 2 is indicated diagrammatically at 1, were arranged so that the needle side or copper wire 5 of the test cell circuit was connected directly to the oscilloscope 16, and a 30 millihenry high frequency choke 21 was inserted between the needle circuit and the circuit which generated the Lissajous figure 15. A protector 22 of a special type consisting of a piece of silicone-treated paper between a plate and a spring electrode was provided to protect the oscilloscope in case of flash-over between the needle 7 and tube 8 in FIGURE 1.

The following specific examples are given to more fully illustrate the invention. In the first five examples, the

majority of the tests were carried out at approximately 92 to 94 mm. Hg pressure, since at this pressure the light to be visually observed is more readily and conveniently obtained than at higher pressures. Too low a pressure is of course avoided, such as would give the glow phenomena previously referred to.

Example 1

The test cell described above was evacuated to less than 0.05 mm. Hg pressure. Then, octafluoro-1,4-dithiane was admitted as the saturated vapor at room temperature (92 mm. Hg pressure). Sixty cycle alternating current was applied and the voltage was gradually raised. The results obtained by visual observation were as follows:

Time elapsed, minutes	Voltage	Observation
2	2,640	Small blue corona, at needle tip, twinkled a few times and disappeared.
6	3,170	Corona restored which twinkled, giving intermittent corona.
20	3,170	Corona extinguished.
27	3,170	Corona still completely extinguished.

Under 50 $\times$ magnification, the tip of the needle was found to be covered with a transparent cap of resinlike material. There was no deposit on the copper tube electrode.

Example 2

In the same manner as Example 1, benzene at 88 mm. Hg pressure was admitted to the test cell. The following observations were made:

Time elapsed, minutes	Voltage	Observations
1	1,350	Twinkled once.
3	1,550	Twinkled a few times only.
5	1,640	Twinkled off and on, with off time increasing.
17	1,640	Corona extinguished.
27	1,640	Corona remained extinguished.

Thus, benzene in the vapor phase extinguishes corona. The tip of the needle was found to have a thin, resinlike coating.

Example 3

After evacuating the test cell to less than 0.05 mm. Hg, benzene was charged to the cell to 30 mm. Hg pressure; then sufficient sulfur hexafluoride was added to bring the total pressure to 94 mm. Hg. The gases were mixed as described earlier. The mixture contained 32 mol percent of benzene and 68 mol percent of sulfur hexafluoride. The following observations were made on this mixture, using 60 cycle alternating current:

Time elapsed, minutes	Voltage	Observations
1	1,310	Faint twinkling; stopped.
4	1,910	Do.
5	2,100	Corona, but weakening.
12	2,100	Corona extinguished.
14	2,370	Corona reestablished, twinkling.
22	2,370	Corona extinguished completely for a number of minutes.

The needle tip had a deposit of dark, resinous material on it. Thus, mixtures of benzene and sulfur hexafluoride extinguish corona.

In the same manner, a mixture containing 32 mol per-

cent of benzene and 68 mol percent of perfluorocyclobutane at a total pressure of 114 mm. was tested. The following was observed:

Time elapsed, minutes	Voltage	Observations
3	2,160	Tiny twinkle.
5	2,440	Faint corona, some twinkling.
7	2,440	Corona extinguished.
14	2,830	Corona reestablished, goes off and on.
17	2,850	Corona extinguished.
25	2,850	Corona remains extinguished.
26	2,850	Slight twinkle.
31	2,850	Corona extinguished completely for the last 5 minutes.

This example demonstrates that benzene, in mixtures with substances which do not extinguish corona, also extinguishes corona.

Example 4

It was found that each of the mixtures shown in the following table effectively extinguished corona under approximately the same conditions as described in Example 3.

Corona-suppressing Substance A	Dielectric Gas B with which tested	Total pressure, mm. Hg.	Proportion A/B by mol percent
30 Vinyl fluoride	Sulfur hexafluoride	94	32/68
Acrylonitrile	do	94	32/68
Butadiene	do	94	32/68
Cyclohexane	do	94	32/68
Cyclohexene	do	94	32/68
Ethylene	do	94	32/68
Isobutylene	do	94	32/68
Neopentane	do	94	32/68
35 Nitromethane	do	94	32/68
Propylene	do	94	32/68
Propylene oxide	do	94	32/68
Vinylidene fluoride	do	94	32/68
Octafluoro-1,4-dithiane	do	188	50/50
Do	do	94	32/68
40 Carbon disulfide	do	94	32/68
Do	Octafluorocyclobutane	94	32/68
1,4-dioxane	Sulfur hexafluoride	94	34/66
Tetrafluoroethylene	do	94	32/68
Toluene	do	94	28/72
Benzene	do	180	17/83
45 Octafluoro-1,4-dithiane	Octafluorocyclobutane	94	32/68
Do	do	188	50/50
Perfluoro(2-n-butyltetrahydrofuran)	Sulfur hexafluoride	180	16/84

Example 5

The following examples were carried out as in Example 3, except that the steel sewing machine needle (7 in FIGURE 1) was replaced with a piece of copper wire (B & S #22) filed to a sharp point. In each case corona was extinguished under approximately the same conditions as given in Example 3.

Corona-suppressing Substance A	Dielectric Gas B with which tested	Total pressure, mm. Hg.	Proportion A/B by mol percent
60 Benzene	Sulfur hexafluoride	88	100/0
Do	94	32/68	
Do	94	32/68	
Carbon disulfide	Sulfur hexafluoride	94	100/0
65 Do	Octafluorocyclobutane	94	32/68
Octafluoro-1,4-dithiane	do	94	100/0
Propane	Sulfur hexafluoride	94	32/68
Propylene oxide	do	94	32/68
70 Do	Octafluorocyclobutane	94	32/68

Thus, the nature of the electrode (i.e., steel or copper) has no effect on the extinguishment of corona.

Examples 6 to 8, inclusive, were carried out at ordinary room temperature and atmospheric pressure.

7
Example 6

Using the test apparatus described above, except that the needle was placed about one-half inch from the copper tube, a test was carried out with sulfur hexafluoride at one atmosphere pressure absolute. At a voltage of about 6600, light appeared and remained steady by visual observation at voltages of 6600 to 6700 for 35 minutes.

Octafluoro-1,4-dithiane was then added to form a small pool in the bottom of the flask. After resealing, the system was partially evacuated until rapid evaporation of the dithiane occurred (liquid still remained); then sufficient sulfur hexafluoride was added to bring the total pressure to one atmosphere absolute. Mixing was carried out by heating a small area of the flask, causing convection in the vapors (vapor pressure of octafluoro-1,4-dithiane equals 90 mm. Hg). Voltage was then applied to the electrodes with the following results:

Time elapsed, minutes	Voltage	Observations
0	6,700	No visible light.
1	8,000	Faint light.
6	8,000	Light flickering.
9	8,000	Light extinguished.
32	8,000	Light remained extinguished; power off.
84	7,130	Power on; no light.
86	8,090	No light.
89	10,260	Light flickered and disappeared.
92	10,260	No light.
102	10,260	Do.

The needle electrode was later found to have a white, slightly rough-appearing resinous cap on its tip.

Example 7

In the same manner as the previous example, a mixture of benzene and sulfur hexafluoride (benzene partial pressure equals 100 mm., total pressure equals 1 atmos.) was tested with the following results:

Time elapsed, minutes	Voltage	Observations
1	6,000	Weak, flickering light.
4	6,520	Do.
6	6,520	Light off and on, mostly off.
8	6,520	Light off.
30	6,520	Light remained off.

On examination, the needle electrode was found to have a small, lumpy, resinous coating at the tip.

Example 8

Example 7 was repeated, substituting octafluorocyclobutane for sulfur hexafluoride. The following observations were made:

NO BENZENE PRESENT

Time elapsed, minutes	Voltage	Observations
5	8,090	Weak light.
31	8,090	Light remained.

BENZENE PRESENT (100 MM. Hg PARTIAL PRESSURE, TOTAL PRESSURE 1 ATMOS.)		
4	7,830	Weak light.
12	7,830	Light extinguished.
31	7,830	Light remained extinguished.

The needle electrode was later found to have a transparent, resinous deposit covering the tip with a dark spot on one side.

Example 9

The films or coatings formed on the tips of the needles (where the corona occurred) were shown to be semi-conductors or non-conductors by the following tests:

- 5 One lead of a direct current resistance measuring unit was connected to an unused steel needle and the other to a pool of mercury via an immersed electrode. The ohmmeter indicated infinite resistance as the needle was lowered toward the mercury pool until contact was made 10 when zero resistance was indicated, i.e., a short circuit. Needles used in the corona suppression tests were carried through the same test. As the tip of the needles came in contact with the mercury, a zero resistance was not obtained. Instead, either infinite resistance or a rather 15 high resistance, but not infinite, was obtained. The intermediate resistance indicated a semi-conductor.

- The semi-conductive nature of the deposits was confirmed by putting a 10,000-ohm resistor in series with the needle, connecting an oscilloscope across the resistor, 20 and applying a fraction of a volt to 6 volts 60-cycle alternating current to the circuit. The amplitude of the cycles was increased or decreased with needle immersion depth, again indicating the semi-conductive nature of the deposit.

- 25 Tests of the various deposits which were found to be present, when tested by the above methods, gave the following results:

30	Source of deposit	Test	Results
1. Octafluoro-1,4-dithiane	A.C.-scope	Non-conductor.	
	D.C.-ohmmeter	Infinite resistance- non-conductor.	
2. Cyclohexene-SF ₆	do	Semi-conductor.	
3. Cyclohexane-SF ₆	do	Do.	
4. Cyclohexane-SF ₆	A.C.-scope	Do.	
5. Octafluoro-1,4-dithiane	do	Do.	
6. Benzene-SF ₆	do	Non-conductor.	
7. Perfluoro-(2-n-butyl-tetrahydrofuran).	do	Do.	

- 40 It was found in each case that the deposit present on the needle after the corona suppressing tests had been run was either a semi-conductor or non-conductor.

- The corona-suppressing gases of the present invention may be used in all types of electrical apparatus where 45 corona discharge takes place, such as in ordinary electrical transformers, vapor-cooled transformers such as disclosed in U.S. Patents 2,777,009 and 2,886,625, communication cables such as described in U.S. Patent 2,221,670, power cables where gaseous dielectrics are 50 employed, capacitors, electronic equipment, or wherever it is desired to prevent permanent damage to the installation by corona discharge.

I claim:

1. A gas-tight electrical apparatus containing at least 55 one electric conductor from which corona-type discharge may occur, a gaseous dielectric surrounding said conductor; said gaseous dielectric comprising as a corona self-suppressing agent octafluoro-1,4-dithiane, the partial pressure of the corona-suppressing agent being at least 30 mm. of mercury.
2. A gas-tight electrical apparatus containing at least one electric conductor from which corona-type discharge may occur, a gaseous dielectric surrounding said conductor; said gaseous dielectric comprising as a corona self-suppressing agent vinylidene fluoride, the partial pressure of the corona-suppressing agent being at least 30 mm. of mercury.
3. A gas-tight electrical apparatus containing at least 65 one electric conductor from which corona-type discharge may occur, a gaseous dielectric surrounding said conductor; said gaseous dielectric comprising as a corona self-suppressing agent benzene, the partial pressure of the corona-suppressing agent being at least 30 mm. of mercury.
4. A gas-tight electrical apparatus containing at least 70

one electric conductor from which corona-type discharge may occur, a gaseous dielectric surrounding said conductor; said gaseous dielectric comprising as a corona self-suppressing agent neopentane, the partial pressure of the corona-suppressing agent being at least 30 mm. of mercury.

5. A gas-tight electrical apparatus containing at least one electric conductor from which corona-type discharge may occur, a gaseous dielectric surrounding said conductor; said gaseous dielectric comprising as a corona self-suppressing agent propylene oxide, the partial pressure of the corona-suppressing agent being at least 30 mm. of mercury.

6. A gas-tight electrical apparatus containing at least one electric conductor from which corona-type discharge may occur, a gaseous dielectric surrounding said conductor; said gaseous dielectric comprising as a corona self-suppressing agent nitromethane, the partial pressure of the corona-suppressing agent being at least 30 mm. of mercury.

7. A gas-tight electrical apparatus containing at least one electrical conductor from which corona-type discharge may occur, a gaseous dielectric surrounding said conductor; said gaseous dielectric comprising as a corona self-suppressing agent an organic compound having a partial

pressure of at least 30 mm. of mercury and selected from the group consisting of octafluoro-1,4-dithiane, vinylidene fluoride, benzene, neopentane, propylene oxide, and nitromethane, said organic compound producing a resinous-type polymeric coating material of the class consisting of non-conductors and semi-conductors of electricity over said electrical conductor when in the presence of ionizing electrical discharge, whereby the ionizing electrical discharge is effectively extinguished.
